UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S WRAP.

SPECIFICATION forming part of Design No. 14,497, dated December 18, 1883.

Application filed October 27, 1883. Term of patent 3½ years.

To all whom it may concern:

Be it known that I, CATHERINE O'HARA, of the city, county, and State of New York, have invented and produced a new and original Design for a Pattern of a Lady's Wrap, (numbered 8,938;) and I do hereby declare that the engraved prints accompanying this specification convey to any one accustomed to using paper patterns a clear understanding of how a garment made up by the pattern will appear.

The design shows loose-fitting sack-fronts, a half-fitted back that has its skirt widened by a plaited fullness at the center and gores at the

sides, wide sleeves that are gathered to stand 15 high over the shoulders, and are draped by plaits in the lower part of their back edges, and also near the front edges, and a standing collar.

What I claim as my invention, and desire 20 to secure by Letters Patent, is—

The design for a lady's wrap, as shown in the engraved prints accompanying this specification.

CATHERINE O'HARA.
